UNITED STATES PATENT OFFICE.

HANS PEDERSEN MITTET, OF AALESUND, NORWAY.

APPARATUS FOR HARD TWISTING OF FINE AND THICK THREADS.

1,352,524.

Specification of Letters Patent. Patented Sept. 14, 1920.

Application filed November 1, 1918. Serial No. 260,752.

To all whom it may concern:

Be it known that I, HANS PEDERSEN MITTET, of Aalesund, in the Kingdom of Norway, have invented certain new and useful 5 Improvements in the Apparatus for Hard Twisting of Fine and Thick Threads; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 Heretofore it has not been possible to produce a thread with a sufficient twist by means of the ordinary twisting machines with ring spindles or fliers, because these machines have not the required dispositions 20 for stretching and guiding the thread, so that only a limited degree of twist can be obtained. But this twist is not sufficient for getting a hard twist on the thread regulated by both twistings.

25 This invention has for its object an apparatus for hard-twisting of the thread, to be placed on an ordinary twisting machine with fliers or a similar machine, by means of which the thread is given a sufficient 30 twist (foretwist and head twist) and from which the thread is passed directly to the twisting machine in a continuous process.

35 By means of this apparatus the twist can be regulated and be got as hard (without bad twist) and perfect as it is required for the purpose, which it has to fulfil. The twisting can be done to the right or to the left.

40 In the drawing a constructional form of a twisting apparatus according to the invention is shown.

Figure 1 is a side view.

Fig. 2 is a section on the line II-II of Fig. 1.

45 Fig. 3 is an end view.

Figs. 4-6 show details in a larger scale.

On the stand 1 screws 2, 3 and 4 are bedded, which are driven from screw wheels 5, 6 and 7 attached to the shaft 8, which 50 for example can be driven by means of a

pulley 9. On the free ends of the screw spindles, twisting frames 10, 11 and 12 are fastened, the end pieces of which may preferably consist of disks 14, 15 and 16, which are fastened to the screws. On the free side 55 of the said disk pulleys 18 and 19 for the thread 20 coming from the thread reels 21 are journaled. On the disks is further fastened a pipe 24, the free end of which is connected with and led through a ring 60 25, which surrounds the thread reel. This ring is connected to the disks by means of rods 26. The pipe mentioned above serves to lead the thread from the thread reels and may be furnished with a lateral cutting 65 28 in order to facilitate the thread to enter the pipe. From the pipe the thread is led on to the pulley 18 and from this over the pulley 19 and further through a bore 29 made in the screw spindle, in which the 70 twisting takes place, and further over the feeding disks 30 and 31, which are fastened on shafts 33 and 34 connected with each other by means of gear wheels 35 and 36 and are driven from the pulley 38 by a belt, 75 said belt coming from the twisting machine. The thread is now led on to the twisting machine with fliers, where the head twist is carried out.

The spindles 40 of the thread reels which 80 are entered into the axial bore 29 in the screw spindles are on their inner end furnished with a nose 43, which projects into a slot made in the disks 14, 15, 16 and is furnished with a groove 44 in order to permit the thread to pass. The outer end of 85 the spindles are journaled in the bearings 45, 46 and 47 in a manner, which facilitates the disengaging. The bearings are fastened to brackets mounted on the upstanding end 90 piece 48. These bearings consist of a fixed base member 50, and a movable upper part 51 which can be turned about the pivot 52 and kept in its normal position by a spring 53. On the outer part the fixed as well as 95 the rotatable part of the bearing is sloped toward the shaft in order to facilitate the entering of the latter.

For the braking of the thread reels in order to prevent a too quick movement (see 100

Figs. 4-6) an elastic belt 55 is arranged, which travels in a groove 56 made in the thread reel. The belt is led around disks 57 and 58, which are moved up and down 5 on the rods 23 according to axial movement of the thread reel caused by the pull of the thread. Further springs 60 are arranged, which are fastened to an axial sleeve arranged in the thread reel, and press with 10 the free end against the spindle of the thread reel. These arrangements serve to prevent the thread reel from rushing during the stopping of the machine.

I claim:

15 1. An apparatus for hard twisting of fine and thick thread, comprising a screw spindle, a disk fastened on the free end of the spindle, a screw wheel for driving the spindle, pulleys for the thread mounted on 20 the free side of the disk, a ring, rods connecting the ring with the disk, a pipe carried by the ring and through which the thread passes to the pulleys, a reel spindle 25 having one end engaging the screw spindle, and means for mounting the other end of the reel spindle so that it can be readily disengaged.

2. An apparatus for hard twisting of fine and thick thread, comprising a screw spindle, a disk fastened on the free end of the spindle, a screw wheel for operating the spindle, pulleys for the thread mounted on 30 the free side of the disk, a ring, rods connecting the ring with the disk, a pipe carried by the ring and through which the thread passes to the pulleys, a reel spindle having one end engaging the screw spindle, means for mounting the other end of the reel spindle so that it can be readily engaged and disengaged, a thread reel on said spindle, grooved friction disks slidable on 35 the said rods, an elastic belt or the like engaging grooves of the disks and the thread reel, and a pipe fitting into the bore of the 40 thread reel and provided with springs pressing against the spindle, for the purpose of preventing the thread reel from rushing at the stopping of the machine and obtaining a suitable tension in the thread 45 during the twisting.

3. An apparatus for hard twisting of fine and thick thread, comprising a screw spindle, a disk fastened on the free end of a spindle, a screw wheel for operating the 50 spindle, pulleys for the thread mounted on the free side of the disk, a ring, rods connecting the ring with the disk, a reel spindle having one end engaging the screw spindle, means for mounting the other end 55 of the spindle so that it can easily be disengaged, and a pipe carried by the said ring and serving as a conduit for the thread from the thread reel to the pulleys, said pipe being provided on one side with a cut

so that the thread can be guided to its place 60 in the pipe through said cut.

4. An apparatus for hard twisting of fine and thick thread, comprising a screw spindle, a disk fastened on the free end of a spindle, a screw wheel for operating the 70 spindle, pulleys for the thread mounted on the free side of the disk, a ring, rods connecting the ring with the disk, a pipe carried by the ring and through which the thread passes to the pulleys, a reel spindle 75 having one end provided with a shoulder and a groove, and engaging the bore of the screw spindle, and means for mounting the other end of the spindle so that it can be easily disengaged.

5. An apparatus for hard twisting of fine and thick thread comprising a screw spindle, a disk fastened on the free end of a spindle, a screw wheel for operating the 80 spindle, pulleys for the thread mounted on the free side of the disk, a ring, rods connecting the ring with the disk, a pipe carried by the ring and through which the thread passes to the pulleys, a reel spindle having one end provided with a shoulder and a groove and 85 projecting into the bore of the screw spindle, and a bearing for the other end of the reel spindle, said bearing consisting of a fixed member and a pivoted and spring-pressed member, the members sloping on the 90 front side in order to facilitate the introduction and removal of the spindle from the bearing when changing the thread reel.

6. In a twisting apparatus, a revolute twisting spindle, guide pulleys adjacent one 100 end of said spindle, a reel spindle in alignment with the twisting spindle a reel slidably mounted on the spindle, and a tubular guide through which the thread passes from the reel to and over the guide pulleys and 105 thence to the twisting spindle.

7. In a twisting apparatus, a revolute twisting spindle, a frame carried by the spindle at one end thereof, guide pulleys carried by the frame adjacent the spindle, a 110 reel spindle within the frame and in alignment with the twisting spindle, and a tubular guide for the thread, said guide being carried by the said frame and extending from the outer end thereof adjacent to the 115 guide pulleys.

8. In a twisting apparatus, a revolute spindle, a skeleton frame carried by the spindle at one end thereof, a reel spindle within the frame and in alignment with the 120 revolute spindle, a reel slidably mounted on the spindle and having a grooved head, grooved disks slidably mounted on the skeleton frame, and an elastic belt engaging the reel head and disks.

9. In a twisting apparatus, a support, a revolute spindle mounted on the support and having a bore, a reel spindle having one

end engaging the bore of the revoluble spindle, and a bearing for the other end of the reel spindle, said bearing comprising a fixed member and a movable spring pressed 5 member, said members having opposed beveled faces to permit the spindle to be readily introduced into or removed from said bearing.

In testimony that I claim the foregoing as my invention, I have signed my name in 10 presence of two subscribing witnesses.

HANS PEDERSEN MITTET.
